UNITED STATES PATENT OFFICE.

WILLIAM E. DINWIDDIE, OF CAPPON, ALBERTA, CANADA.

HARMONIC ATTACHMENT FOR PIANO OR ORGAN KEYBOARDS.

1,246,068.

Specification of Letters Patent. Patented Nov. 13, 1917.

Application filed May 21, 1913. Serial No. 768,926.

To all whom it may concern:

Be it known that I, WILLIAM E. DINWIDDIE, a citizen of the United States, residing at Cappon, in the Province of Alberta and Dominion of Canada, have invented a new and useful Improvement in Harmonic Attachments for Piano or Organ Keyboards, of which the following is a specification.

10 This invention relates to a keyboard attachment adapted to be placed in position upon either an organ or piano, whereby the chords of various musical compositions may be played without the player fingering the individual notes or being acquainted with the names of the various keys.

The invention also includes a false keyboard, employed for the reason that by using the same, all of the keys visible are normally 20 in the same horizontal plane, whereas upon the regular keyboard the back keys project above the white keys and are also of less length.

The invention consists essentially of one 25 or more flexible bars arranged above the keyboard and extending transversely across the keys, said bars being provided with foot portions properly spaced upon each bar so that when portions of the bars are depressed, the foot portions of the depressed part of the bar will carry downwardly the keys engaged by said foot portions, leaving undisturbed the remaining keys.

It will be understood of course, that the 35 foot portions of each bar are so spaced as to engage those keys sounding notes common to a certain chord, and as many bars may be employed as it may be necessary.

While many compositions may be played 40 in a satisfactory manner by the use of three bars, I have found that by using five a greater variety may be obtained and the use of five bars also permits the introduction of chords of a related key and also the playing of pieces in two keys without longitudinal shifting of the flexible bars.

It will also be understood that by shifting said bars the shifting of the foot portions from engagement with one set of notes will 50 transpose from one key to another so that pieces may be played in any major key without substituting additional bars. Bars may also be provided for playing minor keys by proper grouping of the foot portions.

55 It will also be understood that in playing

the device the hand is slipped along the bars and the proper bar is depressed, but that as the bars are flexible the entire bar is not depressed to such an extent as to sound all of the notes throughout the whole range of 60 the keyboard for which foot portions are provided.

For example if the treble portion of a bar is depressed only those notes of the chord in a treble will be sounded, and consequently 65 by sliding the hands along a bar the chords may be sounded in any particular register or portion of the keyboard.

The invention also consists of the novel features of construction hereinafter described, pointed out in the claims and shown in the accompanying drawings, in which,

Figure 1 is a plan view of the preferred construction centrally broken away, a portion of an organ casing being shown and 75 a false keyboard being used.

Fig. 2 is an enlarged inverted plan view of an end portion of the device.

Fig. 3 is an elevation of an end portion, the foot portions being shown only upon the 80 front bar.

Fig. 4 is a section on the line 4—4 of Fig. 1.

Fig. 5 is a plan view partly broken away illustrating a modified form for holding the 85 bars in position, the foot portions being added so as to show their relative arrangement upon the bars.

Fig. 6 is a section on the line 6—6 of Fig. 5.

In constructing the preferred form of the device, I provide a suitable frame comprising a longitudinally extending rear member 1, two forwardly projecting end members 2 and a front member 2^a connecting the end 95 members 2. In the device thus constructed a series of false keys 3 are suitably carried by the underside of the member 1, being mounted thereupon in any suitable manner which will permit their depression and 100 guided by pins 1^b which extend between the keys 3. These keys are all of the same length and those which extend above the white keys are provided with small blocks 4 upon their underside as shown in Fig. 2, said blocks resting upon the white keys and holding the false keys 3 in exactly the same horizontal plane as the false keys which rest upon the black keys of the regular keyboard.

It will be understood that this false key- 110

board is used as a matter of convenience and does not form an essential part of the playing apparatus to be next described.

The playing apparatus consists of a series of flexible bars 5 formed of any suitable material and which extend transversely across the keys from one end of the keyboard to the other and these bars are provided upon their underfaces with suitable downwardly extending projections or foot portions 6, which are grouped upon the bars to engage the keys forming certain chords.

The bars 5 may be supported in any desired manner and in the construction shown in Fig. 1, the ends of the bars are supported upon the blocks 2, and the various bars are connected together by means of the spring clamps 7, or in any other suitable manner, so that all of the bars will shift lengthwise at the same time and to the same extent. Upon one of the blocks 2 I provide a suitable rack 8 and a suitable notched plate 9 for the purpose of receiving the ends of the clamps 7 thereby locking the bars against shifting while in use. This locking mechanism also serves to indicate the position of the bars for use in certain keys as for example with the clamps in the fourth notch as shown in Figs. 1 and 3 the foot portions are so grouped that the bars will play chords in the keys of C and G. By shifting the clamp at the right hand end from one notch to another the bars are also shifted so as to transpose successively from one key to another, or in the case of five or more bars from one group of keys to another.

While it is preferable, where possible, to support the bars from the ends, it frequently happens that there is not a sufficient shelf at the ends of the keyboard to permit the proper longitudinal shifting of the bars when supported as shown in Fig. 1.

It therefore becomes necessary to cut off the surplus end portions of the bars and support them from the frame 1. This support can be by means of any suitable form of spring arm which will permit ready downward movement of the bars and at the same time aid their return to normal position.

It is also essential that these spring arms be so arranged that the arms which support one bar will not interfere with downward movement of the other bars, and it is therefore obvious that if said arms were secured directly either to the top or bottom faces of the bars, the pressing of one bar would carry other bars downwardly with the one pressed. I therefore prefer to employ flat spring arms 10 and in order that all of said arms may shift together, I secure them at their inner ends to a plate 11 adjustable along the frame 1, and such adjustment may be provided for by means of a series of perforations 12, formed in the central portion

of the strip 11, and adapted to be engaged by a pin 13, carried by the frame 1.

In order to prevent the strip 11 from swinging upon the pin 13 as a pivot, the end portion is slotted as shown at 14, and a second pin 15 projects into said slot.

The arms 10 are curved downwardly and each bar is secured at its outer end to a foot portion 6 of the bar which it is designed to support. For some chord arrangements especially where there are five or more bars, it will be necessary to have some of the arms pass around foot portions of another bar, but this can be readily accomplished by reducing the width of the bar, cutting it out upon the side or slotting it.

I prefer to use a flat strip for the arms as there would, in this case, be less tendency upon the part of the arm to give laterally and thereby allow accidental longitudinal shifting of the bars under the sliding pressure of the hands.

It will be obvious that in the form shown in Fig. 5 the shifting of the strip 11 and the engagement of the pin 13 with successive perforations produces exactly the same transposing from one key to another as is produced by shifting the clamp 7 in the form shown in Fig. 1.

In order to more clearly illustrate the operation of the device, it will be assumed that when the bars are in the positions shown in Figs. 1 and 5, that is with the bars locked in one case by the clamp 7 engaging a middle notch and in the other case by the pin 13 engaging the middle perforation 12 that the keys C and G are the ones to be played in.

Assuming that the first key at the left hand end (Fig. 5) is D and that the first key shown complete in the central portion is C it will be obvious from the dotting of the foot portions that the third bar from the front will play the tonic chord, or with the bars locked in the position shown denote C, E, and G. The fourth bar carries four foot portions to the octave engaging in this key the notes G, B, D and F thus giving the chord of the dominant seventh, and the last bar has three foot portions to the octave engaging the notes F, A, C forming the chord of the sub-dominant.

This gives the principal chords in this key, and these three bars can be employed, by themselves if desired, but by having five bars I allow for the use of chords in a related key and also prepare for the playing in two keys without longitudinal shifting of the bars.

In order to do this the first bar is provided with foot portions so grouped as to form the tonic chord in the key of G when the bars are in such position that the third bar sounds the tonic in the key of C, and the second bar gives the dominant seventh in the key of G. This second bar which lies ad-

5 jacent to the bar having the tonic of the key of C also provides means for giving in said key the F sharp frequently found as an accidental in said key. This arrangement of the foot portions is made quite clear in Fig. 3 where those carried by the first bar are shown in front elevation, and assuming that the highest note on the organ is F it will be noted that these foot portions bear 10 upon the false keys overlying the keys producing the notes G, B and D.

What I claim is:—

- 15 1. The combination with a musical keyboard, of a plurality of flexible bars arranged above said keyboard, and foot portions spaced along each of said bars in alinement with selected keys, and adapted to engage them on depression of portions of the bars.
- 20 2. The combination with a piano or organ keyboard, of false keys placed above and adjacent the same, flexible bars, and means carried by the flexible bars for engaging and depressing selected false keys, said false 25 keys actuating the organ or piano keys beneath them.
- 30 3. The combination with a piano or organ keyboard, of a false keyboard resting thereon, flexible bars arranged above and adjacent to said false keyboard, foot portions carried by the bars, the foot portions of each bar being spaced on said bar to actuate keys sounding tones of a musical chord, said bars being adjustable longitudinally, and means 35 for holding the bars in adjusted position.
- 35 4. The combination with the keyboard of an organ or piano, of a false keyboard carried thereby and registering with the regular keyboard, flexible bars arranged above and

adjacent said false keyboard, and foot portions carried by said bars and located to depress selected keys upon depression of portions of the bars, the foot portions of each bar being spaced to produce chords. 40

5. The combination with a piano or organ keyboard, of a false keyboard mounted thereon, a series of flexible bars arranged above the false keyboard, foot portions spaced along each of said bars in position to engage keys of the false keyboard, and means for supporting said bars, the foot portions of each bar being located to actuate keys of said false keyboard to produce tones of a chord, the spacing of the foot portions of one bar producing a chord having a definite harmonic relation to those produced by depression of the other bars. 45 50 55

6. The combination with a piano or organ keyboard, of a false keyboard carried thereby, the keys of which correspond to and actuate those of the regular keyboard, all keys of said false keyboard being normally in the same horizontal plane, flexible bars extending over said false keyboard and being longitudinally adjustable, depending 60 65 portions carried by said bars and adapted to engage keys of the false keyboard, the depending portions of one bar being spaced to engage keys to produce a tonic chord, those of an adjacent bar engaging keys to 70 produce the chord of the dominant seventh, and the depending portions of the remaining bars engaging keys to produce related chords.
